UNITED STATES PATENT OFFICE.

ARTHUR EDWARD SENTINELLA, OF WATERLOO ROAD, LONDON, ENGLAND, ASSIGNOR TO
BOWDEN WIRE LIMITED, OF WILLESDEN JUNCTION, ENGLAND.

BOWDEN-WIRE MECHANISM.

1,319,627.

Specification of Letters Patent.

Patented Oct. 21, 1919.

Application filed June 11, 1919. Serial No. 303,517.

To all whom it may concern:

Be it known that I, ARTHUR EDWARD SENTINELLA, a subject of His Majesty the King of England, and resident of Waterloo Road, in the county of London, Kingdom of England, have invented certain new and useful Improvements in or Connected with Bowden-Wire Mechanism, of which the following is a specification.

10 This invention relates to Bowden wire mechanism.

When using Bowden wire power transmitting mechanism, and when a pivoted lever or device is employed to operate said mechanism, it is, as is well known, very desirable and often necessary that at least the end of the inner member of the mechanism connected to and operated by said pivoted lever or device should always move in a straight path in order to reduce the strain upon, the wear of, and the liability to bending, distortion and breakage of the member to a minimum, and in order to obtain a straight pull upon and a maximum actuation of the member with as little effort upon the lever or device as possible.

It is, therefore, the object of the invention to provide improved, simple and efficient apparatus by the use of which the above mentioned advantages are attained, and the difficulties sometimes experienced with this class of apparatus, in providing an efficient operative connection between an operated member which moves in a straight line and a lever which operates said member and moves through an arc owing to its pivotal mounting, are overcome.

The invention provides means for controlling Bowden wire mechanism, said means comprising an operating lever or device pivoted or hinged by one of its ends to a clamp, clip or support and operatively connected, intermediate its ends and through one or more intermediate links, to a member 45 slidable in a guide which is carried by said clamp, clip or support and serves as an abutment for the outer member of the mechanism, to which slidable member the inner member of the mechanism is secured, the arrangement being such that said inner member is moved in a straight path in the same direction as that of the movement of the slidable member.

The invention will now be described with

reference to the accompanying drawings, in 55 which:—

Figure 1 is a side elevation showing a suitable construction of the improved device in duplicated form,

Fig. 2 is a front elevation of same, and 60

Fig. 3 is an enlarged sectional elevation on the line 3—3 of Fig. 2.

In the example shown, and in each unit, an operating lever or device *a* of bell-crank or right angular formation is pivoted or 65 hinged at *b* by its upper end *c* to a two part clamp *d*, a clip or other support secured or formed on the handle-bar *e*, steering wheel or other convenient part of the cycle, motor 70 cycle, automobile, aeroplane or other vehicle, machine or apparatus to which the invention is applied. A plunger or the like *f* is slidably mounted within or between one or more guides or lugs *f'* fitted or formed on the clamp, clip or other support *d* carrying 75 the lever *a*. The lever *a* is connected intermediate its ends to the adjacent end of the member *f* by one or more links *g* which is or are pivoted at *h* to said lever and at *i* to said end of the member.

The member *f* operated by the lever *a*, *e* fits snugly within or between the guide or guides to slide in a straight path, and is connected to the Bowden wire mechanism. Thus, the plunger or the like *f* is secured to 85 the inner wire *j* of the Bowden wire mechanism such as by means of the nipple *j'*, while the guide or guides *f'* provides or 90 provide an abutment for the adjacent end of the outer member *k* of the mechanism.

The apparatus described above may be so arranged that the two levers *a* can be temporarily locked to one another to move in unison if and when desired. The device may be constructed as a single unit or it can 95 be composed of more than two units.

What I claim is:—

1. A Bowden wire control, comprising a clip, an operating lever pivotally connected at one end to the clip, a guide carried by said clip, a member slidably mounted in the guide and connected to the wire, said member being a hollow sleeve with one end open and the other closed to retain the end of the wire and a link pivotally connected to the 100 lever and to said member.

2. A Bowden wire control, comprising a clip, an operating lever pivotally connected

at one end to the clip, a guide carried by said clip, a member slidably mounted in the guide and connected to the wire, said guide being formed to limit movement of the member in one direction, and means connecting the member and the operating lever.

3. A Bowden wire control, consisting of a two part clip, twin operating levers having one end pivoted to said clip, a tubular guide secured to said clip and having one

end open and the other closed, a hollow sleeve member fitting in said guide having an open end connected with the operating levers and having a closed end abutting against the closed end of said guide and serving to retain the end of a wire in position.

In testimony whereof I have hereunto signed my name.

ARTHUR EDWARD SENTINELLA.

Copies of this patent may be obtained for five cents each, by addressing the "Commissioner of Patents, Washington, D. C."
